UNITED STATES PATENT OFFICE.

PETER J. PAULY, SR., OF ST. LOUIS, MISSOURI.

BOOKCASE.

SPECIFICATION forming part of Letters Patent No. 542,277, dated July 9, 1895.

Application filed October 1, 1894. Serial No. 524,585. (No model.)

To all whom it may concern:

Be it known that I, PETER J. PAULY, Sr., of the city of St. Louis, State of Missouri, have invented certain new and useful Improvements 5 in Bookcases, of which the following is a full, clear, and exact description, reference being had to the accompanying drawings, forming a part hereof.

My invention has relation to improvements 10 in bookcases; and it consists in the novel arrangement and combination of parts more fully set forth in the specification, and pointed out in the claims.

In the drawings, Figure 1 is a perspective 15 view of my invention with parts broken away. Fig. 2 is a bottom plan view of one of the drawers with the casing thereof in section, and Fig. 3 is a vertical longitudinal section taken on the line $x-x$ of Fig. 2.

The object of my invention is to construct 20 a bookcase or cabinet of suitable ornamentation or design, constructed preferably of sheet metal and comprising drawers which are adapted to be partially withdrawn from the 25 case, within which drawers are adapted to be placed books in the manner shown in dotted lines in Fig. 1.

My invention further consists in providing 30 the said drawer with a movable portion or front, which is adapted to be turned in position as shown in Fig. 1, which acts as an additional support for the books when the same are opened, and in other details hereinafter described.

Referring to the drawings, 1 represents a 35 case or cabinet comprising any number of rectangular openings 2, which are formed by partition-walls 3, and which openings are adapted to receive the drawers 4, containing 40 the books 5. Each opening is provided with two guideways 6, which are located adjacent to the opposite vertical walls of the same, and which are adapted to receive loosely, but snugly, the tongues 7, forming a part of the 45 drawer 4.

Secured to the bottom or lower wall of the opening 2 is a stop 8, against which the transverse strip 9, secured to the bottom of the drawer 4, comes in contact for limiting the 50 outward movement of said drawer and further preventing the latter from being entirely withdrawn from said opening.

Pivoted to the under surface of the bottom of the drawer to one side thereof and adapted to swing in a plane substantially parallel to 55 the bottom of the drawer and at a suitable distance from the front end is a plate 10, to the forward edge of which is secured a rectangular-shaped plate 11, the size of which corresponds to the height and width of the opening 2 for completely closing said opening when the drawer is in its normal or closed position. Formed in the plate 10 is a semi-circular slot 12, and passing through said slot and into the bottom of the drawer 4 is a pin 65 13, which acts as a support for said plate 10 in all positions of the latter.

To one edge of the plate 10, or adjacent to the pivotal portion thereof, is a tongued strip 14, which extends a suitable distance beyond 70 the rear edge of the plate, the end of said strip being beveled or mitered, as shown at 15, which miter corresponds with the mitered edge 16, formed on one end of the tongued strip 17, secured to the bottom of the drawer 75 4, whereby when the two miters 15 and 16 cooperate—that is, when the plate 10 is in its closed position, a continuous tongued strip is formed and is received by one of the guideways 6, the miters 15 and 16 limiting the 80 movement of the plate 10 in one direction, and the pin 13 and one end of the slot 12 limiting said plate in the opposite direction.

18 represents a groove, which is located below the bottom of the drawer 4 and adjacent 85 to the longitudinal edges thereof, which is adapted to receive the edge 19 of the plate 10 when the latter is in a closed position, as shown in dotted line in Fig. 2. Under these circumstances the drawer can be completely 90 closed, as shown by drawer 20 in Fig. 1.

In order to successfully operate the drawer, the book 5 is placed within the same in the position as shown in dotted lines in Fig. 1, and if the plate 10 be turned in the position as 95 shown in said figure the book may be opened and will thereby be supported partially by said plate. When it is desired to close the drawer, the plate 10 is turned in the direction as shown by the arrows in Fig. 2, whereby the 100 drawer and its plate, together with the book, (having been previously closed,) may simultaneously be pushed or shoved into the opening 2.

By the use of my invention it is not necessary to remove the book from the drawer for inspecting the same, and it will thus be readily seen that my invention further provides a book-rest and overcomes the tedious and laborious handling of the book.

The front plate 11 of the drawer is provided with a handle 21 and suitable index-plate. (Not shown.)

Having described my invention, what I claim is—

1. A book case comprising a drawer, a plate hinged to the same and adapted to swing in a plane substantially parallel to the bottom 15 of said drawer, suitable means in connection with the drawer bottom for limiting the movement of the hinged plate in one direction, and a vertical front plate for said hinged plate having a suitable handle, substantially as set forth.

2. A book case having a suitable opening, guide-ways located within the same, a drawer adapted to slide within the opening and provided with tongued strips, a plate adapted to 25 swing in a plane substantially parallel to the bottom of the drawer hinged to said drawer and provided with a curved slot, a pin passing through said slot and into said drawer for limiting the movement of the hinged plate

in one direction, and a front plate provided 30 with a suitable handle for closing the opening for the drawer, substantially as set forth.

3. A book case comprising a suitable opening, guide-ways within the same, tongued strips movable within the guide-ways, a 35 drawer to which the said strips are secured, a hinged plate carried by said drawer and having a tongued strip secured to one edge of the same and extending a suitable distance beyond the rear edge thereof, a mitered edge 40 formed on the free edge of said strip and adapted to co-operate with a similar edge formed on one of the tongued strips of the drawer, a semi-circular slot formed in said plate, a pin passing through said slot and into 45 said drawer, a front plate secured to the front edge of the hinged plate and provided with a suitable handle, and a groove forming a part of the drawer for receiving the free edge of the hinged plate when the latter is in a 50 closed position, substantially as set forth.

In testimony whereof I affix my signature in the presence of two witnesses.

PETER J. PAULY, SR.
